UNITED STATES PATENT OFFICE

2,632,169

AMPLIFYING BRASSIÈRE

Ernest Silvani, Roselle, N. J., assignor to Maiden Form Brassiere Co., Inc., New York, N. Y., a corporation of New York

Application November 29, 1951, Serial No. 258,898

1 Claim. (Cl. 2—42)

1

The object of the present invention is to provide an improvement upon that type of brassière incorporating, or having pockets for receiving, pads or rubber cups for amplifying purposes.

This invention relates to that type of brassières into which are permanently built pads or cups. The invention is based upon my discovery that the thickness and bulk of pads heretofore used, including those formed of sponge rubber, may be avoided, with more natural effect and general satisfaction, by a specially formed relatively thin insert for the inner and outer layers of each brassière cup. This insert, as to each cup, consists of two relatively narrow sections of sponge rubber, the sections being joined by a central seam which extends through the inner fabric layer of the cup, and by arching and tensioning the stitching which extends through the two fabric layers and the margins of the inner relatively thin connected sections of sponge rubber or like material. By such means lateral stresses upon the cups, as when the brassière is applied to the wearer with customary elastic elements at the back band, such stitching tension will tend to augment the outwardly arched formation of the cups and maintain them in such positions even when the central arched area of each cup does not directly abut the wearer.

The invention will be described with reference to the accompanying drawings, in which:

Fig. 1 is a perspective view showing an embodiment as worn, the wearer being indicated by dotted lines;

Fig. 2 is an enlarged substantially vertical section taken centrally between the two halves of one cup, the section being taken on the line 2—2 of Fig. 1;

Fig. 3 is a horizontal section on the line 3—3; and

Fig. 4 is a plan view showing one of the two cup inserts.

Referring to the drawings, I have shown at 1 an outer fabric section which forms half of a cup, the second section 1x being identical in form. The two sections of each outer cup fabric are joined by stitching as at 2, and each cup is seamed to a frame consisting of an inner fabric piece 3 and an outer fabric piece 4. As customary, inner frame members 3 are seamed together at 5 and the outer margins are connected to a back band element 6. In practice, this back band may be of two sections with adjustable means for connecting them. Such a back band

2

forms no part of the present invention and is not shown in detail.

Under each outer cup fabric 1, 1x, are two inserts preferably of sponge rubber so as to be yielding and at the same time capable of return to initial position upon release of tensional forces thereon. Each sponge rubber piece 8 is shaped as in Fig. 4 and when the two pieces are brought into abutment, the straight edges at 7 10 will contact and will be seamed together by stitching as at 8x, Fig. 3. This stitching not only connects the two sponge rubber pieces but secures them to inner or lining corresponding pieces of soft fabric indicated at 9. At their margins, 15 the assembled fabric lining pieces and sponge rubber pieces are seamed to the frame 3, 4 by stitches indicated in Fig. 1 at 10. These marginal stitches preferably extend through the outer cup fabrics 1, 1x. Each sponge rubber piece is 20 indicated at 8.

In the embodiment shown, each cup frame is composed of the outer fabric pieces 3 and 4 and corresponding inner fabric pieces 3x and 4x, as shown more particularly in Figs. 2 and 3. Also, 25 as shown in Fig. 2, the base of the brassière may be reinforced by inner band 12 and tapes 13 and 14.

Reference to Figs. 2 and 4 will show that, as to each cup, the inner and outer fabric pieces 30 and the insert pieces 8 of sponge rubber or equivalent material are shaped to provide an outwardly directed arch which terminates above the longitudinal center of the said elements, whereupon the line at the base of the arch gently 35 recedes to the base of the brassière cup. The result is that the cup formation illustrated in Figs. 2 and 3 is maintained by the stitching and augmented by lateral stresses upon the cups during the wearing of the garment. By reason of 40 the thinness and light weight of the insert, the garment itself is light in weight, comfortable, and inasmuch as it lacks the bulk of usual padded brassières, while having adequate amplifying characteristics, the brassière offers very substantial improvement over those in use.

Having described my invention, what I claim and desire to secure by Letters Patent is as follows:

50 A brassière comprising a pair of arched stitched-in-place brassière cups, each of said cups consisting of two substantially half cup segments, a left half segment and a right half segment, each of said segments consisting of an outer fabric, an inner fabric, and an intermediate layer of sponge rubber, said segments hav-

ing substantially the shape of a right triangle with a horizontal base and a vertical leg adapted to be centrally disposed over the breasts, said base segments being a part of the base of said brassière, said triangular left and right segments being stitched together to form said arched cups.

5 ERNEST SILVANI.
